(57) **CLAIM**

The ornamental design for an automatic injector carry pack, as shown and described.

DESCRIPTION

FIG. 1 is a front, right, top, perspective view of an automatic injector carry pack, showing a first embodiment of our new design;

FIG. 2 is a front elevational view thereof, the rear elevational view being identical;

FIG. 3 is a right side elevational view thereof; the left side elevational view being identical;

FIG. 4 is a top plan view thereof;

FIG. 5 is a bottom plan view thereof;

FIG. 6 is a front, right, top, perspective view of an automatic injector carry pack, showing a second embodiment of our new design;

FIG. 7 is a front elevational view thereof, the rear elevational view being identical;

FIG. 8 is a right side elevational view thereof; the left side elevational view being identical;

FIG. 9 is a top plan view thereof; and,

FIG. 10 is a bottom plan view thereof.
